UNITED STATES PATENT OFFICE.

RUDOLPH C. PLEINS, OF ST. PAUL, MINNESOTA, ASSIGNOR TO WESTERN CAR SEAL COMPANY,
OF ST. PAUL, MINNESOTA.

CAR-SEAL.

No. 897,848.

Specification of Letters Patent.

Patented Sept. 1, 1908.

Application filed November 17, 1906. Serial No. 343,887.

To all whom it may concern:

Be it known that I, RUDOLPH C. PLEINS, a citizen of the United States, residing at St. Paul, in the county of Ramsey and State of Minnesota, have invented certain new and useful Improvements in Car-Seals, of which the following is a specification.

My invention relates to improvements in seals for railway cars, etc., its object being 10 to provide a simple construction of seal which is not easily tampered with or possible of second use.

To this end, my invention consists in the features of construction and combination hereinafter particularly described and claimed.

In the accompanying drawings forming part of this specification, Figure 1 is a perspective view of my improved seal, Fig. 2 is a longitudinal section of the same, Fig. 3 is 20 an enlarged section of the locking ends of the seal, Fig. 4 is a plan view of one end of the strap member, and Fig. 5 is a detail of one of the lock members.

As shown in the drawings A represents the 25 strap member of the seal carrying at its free ends coöoperating stud and cap members 2 and 3. The stud member 2 is adapted to be secured in one end of the strap in any suitable manner as by being flanged into an opening 30 4 in the strap as shown in Fig. 2. The stud member is, as shown in Fig. 2, formed in its sides with outwardly and downwardly extending spring tongues 5. Suitably supported in the other end of the strap is a 35 downwardly tapered cap 6 carrying at its lower end an inwardly extending annular flange 7 constituting an opening of sufficient size to receive the stud. When the free ends

of the strap are brought together the cap will pass downwardly over the stud forcing the 40 spring tongues inward until the flange 7 passes below the tongues when the tongues will spring out as shown in Fig. 2 and engage with the inner face of the flange to hold the members locked together.

In Fig. 1 is shown the locked or closed position of the seal. When it is desired to open the seal the strap A can be broken at the point where it is weakened by the opening 8. It will be evident that the seal can 50 not be used again nor can the end of the strap where broken be arranged so as to give it the appearance of being sealed, as there is no opening in connection with the cap into which it can be forced.

Claim:

In a seal of the class described, the combination with a locking strap, of a single piece cap carried by one end of said strap, an inwardly extending flange carried by the 60 inner end of said cap and constituting a central opening therefor, a stud carried by the other end of said strap, said stud being adapted to pass through and fit closely in said opening, and outwardly directed spring 65 tongues 5 carried by said stud and extending toward the inner end thereof in position to stand inside said cap and to bear against said flange when said cap and stud are brought together.

In testimony whereof I affix my signature in presence of two witnesses.

RUDOLPH C. PLEINS.

Witnesses:

H. S. JOHNSON,
HATTIE SMITH.
